Primary Examiner — Cynthia Ramirez(74) *Attorney, Agent, or Firm* — Walter | Haverfield LLP;
Sean F. Mellino; D. Peter Hochberg(57) **CLAIM**The ornamental design for a shelf for use in wheeled
containers, trolleys and other load carriers, as shown and
described.**DESCRIPTION**FIG. 1 is a perspective view of the shelf for use in wheeled
containers, trolleys and other load carriers according to the
present invention;FIG. 2 is a top view of the shelf for use in wheeled
containers, trolleys and other load carriers according to the
present invention as shown in FIG. 1;FIG. 3 is a front view of the shelf for use in wheeled
containers, trolleys and other load carriers according to the
present invention as shown in FIG. 1;FIG. 4 is a side view of the shelf for use in wheeled
containers, trolleys and other load carriers according to the
present invention as shown in FIG. 1, it being understood
that the opposing side view is identical; and,FIG. 5 is a bottom view of the shelf for use in wheeled
containers, trolleys and other load carriers according to the
present invention as shown in FIG. 1.The broken lines in FIGS. 1, 3 and 4 are to show portions of
the shelf for use in wheeled containers, trolleys and other
load which form no part of the claimed design.**1 Claim, 4 Drawing Sheets**FIG. 1

FIG. 2

FIG. 3

FIG. 4
